UNITED STATES PATENT OFFICE.

FREDERICK HACKMANN, OF CHICAGO, ILLINOIS, ASSIGNOR TO IDA R. HACKMANN, OF CHICAGO, ILLINOIS.

RAIL ANCHOR.

Application filed November 3, 1924. Serial No. 747,516.

This invention relates to a rail anchor and particularly to a rail anchor which may be removably locked in association with the rail flange and an adjacent tie to prevent relative 5 creeping of the tie and rail.

In devices of this type which have heretofore been generally used, difficulty has been experienced with rail breakage when cars are derailed and removal of such devices for the purpose of replacement of the rail has often rendered the same unfit for reuse.

It is therefore an important object of the present invention to provide a device which 15 overcomes the above disadvantages and which fulfills the requirements set forth in an effective manner.

It is another important object of this invention to provide a rail anchor of the class 20 described wherein a double wedging lock is provided between the rail engaging member and the tie engaging member.

It is also an important object of this invention to provide a rail anchor of the class 25 described which may be readily applied without defacing the rail, which is inexpensive, and which may be reused many times.

Other and further important objects of this invention will be apparent from the disclosures in the specification and the accompanying drawings.

The invention in a preferred form is shown on the drawings, and hereinafter more fully described.

On the drawings:

Figure 1 is a fragmentary top plan view showing a rail and tie and an improved embodiment of the rail anchor of this invention in operative position in connection 40 therewith.

Figure 2 is a section on the line II-II of Figure 1 with parts in elevation.

Figure 3 is a side elevation with the tie shown in section taken along the line 45 III-III of Figure 1.

Figure 4 is a fragmentary section with parts in elevation taken along the line IV-IV of Figure 3.

Figure 5 is an enlarged fragmentary detail section showing the inter-engaging locking teeth on the spring member and on the wedge member.

As shown on the drawings:

The reference numeral 1 indicates a usual 55 rail supporting tie which has a rail 2 sup-

ported thereon in the usual manner, the flange of said rail being designated by the reference numeral 3. The spring member which forms a part of the rail anchor of this invention engages under the flange 3 of the 60 rail 2 and is preferably bent upwardly as shown at 4 to springingly engage the under side of said rail. Said spring member is provided with a hook portion 5 at one end, which engages over one edge of the flange 65 3 as clearly shown in Figures 1 and 2 and the other end of said spring member is provided with a similarly formed hook portion 6 which is provided on its inner face with corrugations or rounded teeth 7 for a purpose 70 to be described hereinafter.

Wedgingly engaged between said hook member 6 and that flange of the rail opposite the hook member 5, is a web 8, of a flanged member 9, the lower flange of 75 which is provided with corrugations or rounded teeth 10 that are adapted to coact with and lockingly engage the rounded teeth 6 of the spring member (Figures 4 and 5). 80 As will be noted from Figures 2 and 4, the web 8 of the flange member 9 is tapered or wedge-shaped and integrally formed at one end of said flange member is a tie engaging plate 11, which is preferably of somewhat greater width than the flange member, and which extends downwardly substantially at right angles thereto in order to abut the side of the tie 1. A reinforcing web or member 12 is pref- 90 erably provided as an integral part of the flange member 9 and the tie engaging member 11, as clearly shown in Figures 2 and 3.

In applying the rail anchor of this invention it is only necessary to place the 95 flange member 9 in position on one flange of the rail preferably the inner flange thereof, with the tie engaging member 11 abutting the side of an adjacent tie as shown. The hook portion 5 of the spring member 100 may then be engaged over the outside edge of the lower flange of the rail 2 and the hook portion 6 is engaged with the flange member 9 with the rounded teeth 7 on the inner face of said hook member engaged 105 with the rounded teeth 10 on said lower flange. The spring member is then driven toward the tie with any suitable tool thus causing a locking wedging engagement between said spring member and the flange 110

member 9 and since said flange member 9 is provided with the tie abutting portion 11, relative creeping movement between the tie and rail is effectively prevented by the 5 application of my improved rail anchor in the manner mentioned. In order to remove this rail anchor, as may be desirable in cases where the rail is to be replaced, a reversal 10 of the previous operation need only be effected—that is the spring member may be driven away from the tie to release the locking wedging engagement between the same and the flange member 9:

By the use of the rail anchor of this 15 invention it is possible to securely anchor the rail to prevent relative creeping movement of the rail and tie and at the same time there is no danger of breakage of the rail flange in case a car should become accidentally derailed, as in the case when ordinary 20 type rail anchors are used. It should also be noted that no undue stress is placed on the spring member when the anchor is removed for replacement of the rail so that 25 this anchor may be reused many times.

It will be apparent that the construction 30 of the rail anchor of this invention is simple and inexpensive and the ease of application thereto to a rail road bed is obvious.

I am aware that numerous details of construction may be varied without departing 35 from the principles of this invention, and I therefore do not purpose limiting the patent granted hereon otherwise than necessitated by the prior art.

I claim as my invention:

1. A rail anchor comprising a spring member adapted to be engaged over one 40 edge of a rail flange and springingly engaging the bottom of the rail, a tie engag-

ing member having a vertical web and upper and lower flanges wedgingly engaged between said spring member and the other edge of the rail flange, and inter-engaging 45 locking teeth on said spring member and on the lower flange of said tie engaging member.

2. A rail anchor, comprising a spring member terminating at each end in a hook portion, one of said hook portions being adapted to engage over one edge of a rail flange, a tie engaging member having a vertical web and upper and lower flanges, said web being adapted to be wedgingly engaged 50 between said spring member and the other edge of said rail flange, the other hook portion of said spring member being adapted to engage the lower flange of said tie 55 engaging member, and interlocking teeth formed on the engaging surfaces of said lower flange and said hook portion.

3. A rail anchor, comprising a spring member having an upwardly convex middle portion adapted to engage the bottom 60 of the rail and terminating at each end in a hook portion, one of said hook portions being adapted to engage over one edge of a rail flange, a tie engaging member having a vertical web and upper and lower 65 flanges, said flanges being adapted to engage the upper and lower faces of the other edge of said rail flange and said web being adapted to be wedgingly engaged between 70 said spring member and the other edge of said rail flange, the other hook portion of said spring member being adapted to engage the lower flange of said tie 75 engaging member.

In testimony whereof I have hereunto 80 subscribed my name.

FREDERICK HACKMANN.
